CLAIM

The ornamental design for a car seat activity panel, as shown and described.

DESCRIPTION

FIG. 1 is a perspective view of a car seat activity panel suspended from a vehicle headrest showing my new design; FIG. 2 is a front view in elevation thereof; FIG. 3 is a side view thereof; FIG. 4 is a rear view in elevation thereof; FIG. 5 is an opposite side view thereof to that of FIG. 3; FIG. 6 is a top plan view thereof; and, FIG. 7 is a bottom plan view thereof.

The broken line showing of a vehicle headrest in FIG. 1 is for illustrative purposes only and forms no part of the claimed design.
